ATTORNEY

UNITED STATES PATENT OFFICE.

THOMAS A. WALSH, OF YONKERS, NEW YORK.

FILE-BOX.

No. 873,473.

Specification of Letters Patent.

Patented Dec. 10, 1907.

Application filed January 23, 1907. Serial No. 353,671.

To all whom it may concern:

Be it known that I, THOMAS A. WALSH, a citizen of the United States, residing at Yonkers, in the county of Westchester and State of New York, have invented new and useful Improvements in File-Boxes, of which the following is a specification.

My invention relates to file boxes and more particularly to that class containing leaves 10 whereon may be pasted records or cuttings and which may be safely stored and kept from dirt and dust, at the same time they are readily accessible and easy of inspection as will be more fully described in the following 15 specification illustrated in the drawings and pointed out in the appended claims.

In the drawings like reference characters are used to designate the same parts in the several figures.

20 Figure 1 is a perspective view of my improved file box. Fig. 2 is a similar view showing the same closed.

My improved box consists of a case made in the form of a book and having covers 5 hinged to a back 6 the same being made of wood or stout card-board and appropriately covered by cloth or paper. Within the same is bound a number of leaves 7 in any suitable manner and which are adapted to receive 30 scraps, prescriptions, pictures or such articles which are to be filed away and kept for reference. One of the covers 5 is provided with flanges 8 to which are hinged suitable inclosing members 9 and 10 and in the 35 corners formed by these flanges 8 are angle pieces 11 which not only strengthen the flanges but project beyond their outer edges and serve to limit the inward movement of the wings 9 and 10. The other cover 5 is 40 provided with angular sockets 12 formed between angle flanges 122, and which sockets are adapted to receive the free ends of the wings 9 and 10 when they are turned upward as shown in Fig. 2.

45 This device is particularly adapted for the use of filing druggists' prescriptions which

are pasted upon the leaves while the device is open as shown in Fig. 1 and it may be provided with suitable indexing pages also pages containing suitable memorandums and 50 receipts. When all of the pages have received their prescriptions or receipts the device may be stored away for reference and forms a very compact and ornamental receptacle for prescriptions which may be 55 placed upon a book shelf and present the appearance of a book. Suitable locking means 13 may be arranged to hold the covers together while the angle pieces 12 firmly brace the sides and prevent the device from 60 becoming weak and the sides dislocated.

What I claim as new and desire to secure by Letters Patent is:

1. A file box of the class described comprising a back, covers hinged to the sides 65 thereof, one of such covers having devices on its inner sides near one outer corner forming angle sockets, the other cover having side and end flanges projecting from the inner side thereof, angle pieces in the angles between such flanges and projecting beyond 70 their outer edges, and wings hinged to the said flanges of the last mentioned cover and adapted, when in closed position, to bear against such angle pieces and to enter the 75 angle sockets of the other cover.

2. A file box of the class described comprising a back, covers hinged to the sides thereof, one of said covers having devices on its inner side at its outer corners providing 80 angle sockets, the other cover having flanges at its sides and ends extending from its inner face, and wings hinged to such flanges and adapted, when in closed position, to enter the angle sockets of the other cover. 85

In testimony whereof, I affix my signature in presence of two witnesses.

THOMAS A. WALSH.
